CLAIM

The ornamental design for the a front portion of a garment protector, as shown and described.

DESCRIPTION

FIG. 1 is a front plan view of a front portion of a garment protector showing my new design; and,

FIG. 2 is a front perspective view thereof.

The broken line showing of a woman's bust in FIG. 2 is for illustrative purposes only and forms no part of the claimed design.
